HOLDER FOR A PAIR OF BOOTS

Henry J. Barreca, Jersey City, N. J.

Application February 23, 1954, Serial No. 29,162

Term of patent 14 years

(Cl. D7—3)

To all whom it may concern:

Be it known that I, Henry J. Barreca, a citizen of the United States, residing at Jersey City, in the county of Hudson and State of New Jersey, have invented a new, original, and ornamental Design for a Holder for a Pair of Boots, of which the following is a specification, reference being had to the accompanying drawing, forming part thereof.

In the drawing

Fig. 1 is a front elevational view of a holder for a pair of boots, showing my new design;

Fig. 2 is a side elevational view thereof;

Fig. 3 is an enlarged bottom view with the holding strap omitted; and

I claim:

The ornamental design for a holder for a pair of boots, substantially as shown.
